pany, Hartford, Conn., a corporation of Con-
necticut**

Application August 17, 1933. Serial No. 49,048

Term of patent 3½ years

To all whom it may concern:

Be it known that I, ARVID H. NERO, a citizen of the United States of America, residing at West Hartford, in the county of Hartford, State of Connecticut, have invented a new, original, and ornamental Design for a Combination Electric Lamp Guard and Support or Similar Article, of which the following is a specification, reference being had to the accompanying drawing, forming part thereof.

Figure 1 is an elevation view of an electric lamp guard and support embodying my new design.

Figure 2 is an elevation view of the device

shown in Figure 1 looking at the left side of the device.

Figure 3 is a plan view looking down on the device shown in Figure 1.

The design although shown as embodied in an electric lamp guard and support may be used in similar articles.

I claim:—

The ornamental design for a combination electric lamp guard and support or similar article, as shown and described.

ARVID H. NERO.
